UNITED STATES PATENT OFFICE

CHARLES BYRON HARRISON, OF CHICAGO, ILLINOIS

TELEGRAPH PAGE-PRINTING MACHINE

Application filed August 19, 1926. Serial No. 130,278.

This invention relates to printing telegraphy and more particularly to a mechanical page printer, designed to set up various combinations of electrical impulses at the receiving end of a telegraph wire, and to utilize these combinations to automatically print or record in page form, the letters, figures, symbols and functions, as employed in printing telegraphy, when used in connection with the well known five unit Baudot distributor.

The main object of the invention is to provide a practical and inexpensive page printer, composed mainly of typewriter parts and following so closely the lines of an ordinary typewriter throughout, that it would enable companies manufacturing typewriters to assemble them upon orders for users of telegraphic page printers. There are also many other advantages to be derived from the conversion of a standard typewriter into a telegraphic page printer, as they are highly standardized and perfected mechanically, and as employed in the present invention, would be both efficient and economical in operation. It is not a new practice to utilize typewriters as a printing medium for telegraph page printers, but the means heretofore employed to bring the parts of the ordinary typewriter into operation constituted so material a part of the printer that the typewriter itself became a minor part of the apparatus when compared to the cost of the added mechanism.

In the present invention, an object is to provide simple and inexpensive mechanism to bring into operation the parts of the already perfected typewriter for automatic telegraphing purposes, namely a mechanical selecting system, and means for actuating the operative parts of the typewriter.

In some present day page printers, a motor is employed to furnish the power with which to actuate the operative parts of the printer, and at the same time six electro-magnets are necessary. Since there are but from three to seven separate and short power movements necessarily required in the operation of a page printer, namely from one to five movements of the selecting mechanism, the recording of the character or function, and the

stepping forward of the paper carriage in letter space direction, it is an object of the present invention to logically employ seven electro-magnets for these seven actions, and to eliminate the motor together with its cam shaft and accompanying cams, levers, and clutch arrangements which are obviously costly and unnecessary. It will be apparent that a motor constantly consumes current even at times when the printer is idle, and of course is expensive when one is incorporated in each machine.

In the present invention, I employ electro-magnetic means to perform the work of the usual motor with the same efficiency and with much greater rapidity. One of the salient advantages of a power magnet operated printer over that of a motor operated one lies in the instantly available application of power when needed. The moment a contact is closed, the corresponding magnet acts with extreme rapidity and power. It is essential that the printer actions start at the earliest possible moment after the reception of the line signals, and the desired rapidity of action is easily accomplished in the present invention since the sixth or local impulse from the distributor immediately completes the printing action. In a motor operated printer the sixth or local impulse trips a clutch which connects the constantly rotating motor driven spindle with the cam shaft. The cam shaft is then revolved and the printer action takes place during the revolution of the cam shaft. Obviously a magnetically operated printer responds with power much more rapidly than a motor operated printer and from the following it will be apparent why great rapidity is essential. At a speed of fifty words per minute, the total time for receiving a signal and recording it is only one-fifth of a second. In the case of the "carriage return" the carriage must be released and allowed to move back as much as seven inches or more for the beginning of a new line after the line signal has been received and set up in the selecting mechanism. Therefore less than one-fifth of a second is available in which to complete this operation. However it is customary to follow the "carriage return" signal with a "line

feed" signal which allows nearly two-fifths of a second for the operation since the line feed and carriage return actions proceed simultaneously. However, even if two-fifths of 5 a second of time is available, no time can be lost and the sooner the carriage is released and started on its backward movement, after the line signal is received, the more time it will have in which to complete the operation.

10 In the present invention the carriage is released instantly upon reception of the sixth or local impulse, whereas in a motor operated printer the release is not accomplished until the clutch is tripped by the sixth or local impulse and the cam shaft is connected to the 15 rotating motor spindle to be revolved.

In the operation of a page printer, about 10 per cent. of the line time is utilized in the transmission of signals to bring about the 20 various motions of the paper carriage, namely, the line feed, carriage return, shifting and unshifting and the feeding of message blanks. The latter action usually is manually performed. In a printer of the tape type, some 25 of the time lost in operating the line feed, carriage return and the feeding of message blanks is eliminated since these three actions are not required, but not all of the time consumed in their operation is saved since it is 30 necessary in the operation of a tape printer to transmit signals to divide the preamble of the message from the address, the address from the text of the message, the text from the signature, and to indicate the end of a 35 message, etc. Since the difference in the amount of time lost in the operation of the two types of printers is not great, the page printing feature as used in the present invention is more desirable and has advantages 40 over the tape printer. For instance, in a page printer, the message is standard and neat, and ready for delivery to the public upon reception, and does not require the cutting and pasting of the tape on the message blank as 45 in the case of the tape printer.

An important object of the invention therefore, is to provide an apparatus of the character referred to, the operation and parts of which are extremely simple and wherein the 50 various mechanical operations of the printer may be carried out in extremely short time intervals thus permitting the apparatus to be operated at a relatively high speed.

A further object is to provide a page printer 55 having novel selecting means for accomplishing the various mechanical functions thereof.

A further object is to provide a page printer 60 the printing portions of which correspond closely to standard practice in typewriter construction thereby simplifying the structure and operation of the device, and to provide novel means for selecting the type to be impressed upon the page or to select the 65 various other mechanical elements for ac-

complishing such other functions as case shifting, shift releasing, carriage returning, line feeding, and the spacing between words.

A further object is to provide a page printer 70 wherein the usual complicated mechanisms involving motor drive means and clutches, and gearing associated therewith are eliminated, and to substitute therefor simple electro-magnetic operating means controlled by the Baudot distributor previously referred to.

A further object is to provide an apparatus 75 of the character just mentioned wherein a plurality of electro-magnetic relays are employed in conjunction with the distributor 80 for selecting the mechanical elements to be actuated, and to provide novel electro-magnetic operating means for the mechanical elements of the electro-magnetic actuating means operating in conjunction with the selecting relays in such a manner that the selection of mechanical elements to be operated are maintained in operative position until actuation has been accomplished, whereupon the selecting means and elements controlled 85 thereby are automatically returned to normal position.

A further object is to provide a plurality 90 of selector rods having cams associated therewith for selecting the proper mechanical elements to be actuated, the cams being co-related 95 in such a manner that it is impossible for more than one mechanical function to be performed at one actuation.

A further object is to provide a page printer 100 of the character outlined wherein the actuation of one of the mechanical elements of the apparatus is dependent upon such element having been pre-selected so that no actuation takes place unless some printing character or mechanical control means has been previously selected for actuation by the distributor and the elements controlled thereby.

A further object is to provide a page printer 110 wherein only a single electrical impulse is necessary to complete a given mechanical function and to return the operating elements to normal position whereby these operations may be accomplished in the shortest possible 115 time.

A further object is to provide a plurality 120 of actuating electro-magnets associated with and electrically connected to the relays and distributor, an electro-magnet for actuating the mechanical elements selected by the distributor, and a source of current for actuating the electro-magnets, movement of the actuating means to operative position being adapted to break the electrical circuits controlling the electro-magnets to permit the various mechanical devices to automatically 125 return to normal position.

A further object is to provide a page printer 130 having a carriage and platen carried there-

by of a type closely similar to the usual type-writer carriage, and to provide novel means for returning the carriage to its initial position at the end of each line.

5 A further object is to provide novel means for causing the carriage to travel one space upon the completion of each character impression upon the page.

10 Other objects and advantages of the invention will become apparent during the course of the following description.

In the drawings I have shown one embodiment of the invention. In this showing,

15 Figure 1 is a rear diagrammatic elevation of the page printer showing the electrical connections thereto,

20 Figure 2 is a fragmentary perspective of a portion of the selecting and printing apparatus,

25 Figure 3 is a rear elevation of the printer, Figure 4 is a transverse sectional view showing a portion of the operating elements of the printer,

30 Figure 5 is a detail sectional view through the spring operated carriage returning device,

Figure 6 is a detail perspective of one of the printer bars and associated elements, and,

35 Figure 7 is a fragmentary perspective of a portion of the space feed release mechanism.

Referring to the drawings, the numeral 10 designates the printing apparatus as a whole which is closely similar in general construction to the ordinary typewriter.

40 The printer comprises vertical frame members 11 and lower horizontal frame portions 12 supported upon suitable legs 13. An upper frame portion 14 is formed integral with the side frame members and supports a carriage indicated as a whole by the numeral 15.

45 The carriage is provided with end frame members 16 slidable upon bars 17 to permit the carriage to travel longitudinally of the printing apparatus, as will be apparent. An ordinary platen 18 is rotatably supported by the end frame members 16 and is provided at one end with a line feed ratchet 19. A feed pawl 20 is adapted to actuate the ratchet 19. This pawl is pivotally connected at

50 one end as at 21 to one end of a bell crank lever 22, the lever being pivotally connected as at 23 to one of the end frame members 16. A link 24 is pivotally connected at one end to the opposite end member 16, and an operating

55 rod 25 is secured at opposite ends to the free ends of the bell crank lever 22 and link 24. A spring 26 is connected between the pawl 20 and bell crank lever 22 to normally hold the pawl in engagement with the ratchet wheels, 60 while a second spring 27 is connected between the bell crank lever and the end frame 16 to retain the bell crank lever in normal position. Means to be described are provided for actuating the rod 25 to rotate the platen

65 18.

It is the usual practice to provide spring drum means for moving the carriage of a typewriter, the carriage being returned manually to its initial position against the tension of the spring. In the present invention

70 I have reversed this operation and have provided mechanical means for advancing the carriage after each character impression and between words, spring drum means being provided for returning the carriage to its initial position after the completion of each line.

75 As shown in Figures 1, 2 and 5, the numeral 28 designates a drum upon which is wound a cable 29, one end of the cable being secured to the drum as will be apparent. The drum

80 28 is arranged adjacent one end of the printing apparatus, and the opposite end of the cable 29 is secured to the end frame 16 adjacent the opposite end of the apparatus.

85 The drum is supported by stub shafts 31 journaled in suitable bearings 32 supported upon the frame of the apparatus at any suitable point. Since Figure 1 is a view taken

90 from the rear of the apparatus, it will be apparent that movement of the carriage during the printing and spacing operations is

95 from left to right, and this movement is adapted to rotate the drum 28 by means of the cable 29. This action is adapted to wind a spring 33 secured at one end to the shaft

100 31 as at 34, the opposite end of the spring being secured by a pin or the like 35 carried by the drum. Thus it will be apparent that movement of the carriage during

105 normal operation of the apparatus is adapted to place the spring under increasing tension, and this tension is utilized for returning the carriage to its initial position, in a manner

110 to be described.

115 Means are provided for mechanically advancing the carriage step by step upon completion of the printing of each character and between words. As shown in Figures 1 and 2, a rack bar 36 is arranged rearwardly of the carriage and is provided with teeth 37. At its upper extremity, the rack bar is provided with a rearwardly extending horizontal flange 38 for a purpose to be described. The rack bar is secured at its ends to links

120 39 which are pivotally connected as at 40 with the end plates 16 of the carriage. The rack bar is adapted to be maintained in the normal position shown in Figure 2 of the drawings by a spring 40'. Rearwardly of

125 the carriage a rotatable shaft 41 is supported in a bearing 42, preferably of the ball bearing type, and is supported by a stationary portion of the frame of the apparatus. The shaft 41 is provided on its inner end with a pinion 43 normally meshing with the teeth

130 37. The outer end of the shaft 41 is provided with a wheel 44 having ratchet teeth 45 thereon. A holding pawl 46 is pivotally connected

135 to the upper frame 14 as at 47 (see Figure 3) and the opposite end of the pawl is provided

with a tooth 48 which engages the teeth of the ratchet wheel to prevent movement thereof in one direction, as will be obvious. A spring 49 is secured at one end to the pawl 46 and at its opposite end the spring is secured as at 50 to a suitable portion of the upper frame 14. It will be obvious that the spring 14 normally maintains the pawl in engagement with the ratchet wheel as previously described. An operating pawl 51 is arranged adjacent the ratchet wheel and is provided with a tooth 52 adapted to engage the ratchet teeth to effect movement of the ratchet wheel. The pawl 51 is pivotally connected intermediate its ends as at 53 with the free end of a lever 54 having pivotal connection at its opposite end as at 55 with a portion of the frame member 14. The lever 54 is provided with a depending member 56 to which is connected one end of a spring 57, the opposite end of the spring being connected to the lower end of the pawl 51. It will be apparent that the spring 57 is adapted to maintain the tooth 52 in engagement with the teeth of the ratchet wheel. The lever 54 is normally adapted to be drawn upwardly by a coil spring 58, the upper end of which is connected to a vertical extension 59 preferably formed integral with the top frame 14. An operating rod 60 is connected to the lever 54 intermediate its ends and is adapted to be operated by a single spool solenoid 61 controlled in a manner to be described, the rod 60 constituting the armature of the solenoid 61.

As previously stated, the rack bar 36 is normally arranged in the position shown in Figure 2 whereby it will be obvious that a step by step rotation imparted to the ratchet wheel will effect a similar movement of the carriage to provide spaces between letters and words. This step by step movement places the spring 33 under increasing tension until the end of a line is reached whereupon it is desirable to release the rack bar 36 from the pinion 43. It will be apparent that the rack bar is free to swing upwardly due to its pivotal connection with the end frames 16 of the carriage and upward movement is accomplished by vertically moving a slide 62 contacting with the shoulder 38 of the rack bar and controlled in a manner to be described. A latch 63 is secured at one end to one of the frame members 16 and is provided adjacent its lower end with a horizontal portion 64 adapted to snap into position beneath the end of the rack bar when the latter is raised. The latch is also provided with an integral depending portion 65 which is adapted to engage a stop 66 to release the latch and permit the rack bar to drop to normal position when the carriage is returned to the beginning of a line.

Adjacent the rear portion of and within the frame 10, I provide a plurality of pref-

erably vertically arranged operating rods or hook bars 66, which in actual practice are thirty-one in number. Twenty-six of these operating rods constitute type bar operating rods for printing the letters of the alphabet, 76 while the remaining five are for performing other mechanical functions such as letter spacing, line feeding, carriage returning, case shifting, and shift releasing. Each of these operating rods is provided adjacent its lower end with an offset portion 67 providing a hook 68 for a purpose to be described. A coil spring 69 is connected at one end to the lower end of each of the operating rods, the opposite ends of the springs being secured to the lower portion of the frame 10. Aside from their connections with the springs 69, the operating rods are freely movable forwardly and rearwardly at their lower ends for a purpose to be described.

Each of the operating rods which constitute printer bars is similar in construction and only one need be described in detail. Referring to Figure 4 of the drawings, the numeral 70 designates a fixed horizontal pivot or axis rod secured at opposite ends to the frame of the printing apparatus. A plurality of bell crank levers 71 are pivotally mounted upon the rod 70, one bell crank lever being provided for each of the operating rods. Each bell crank lever includes a lower horizontal lever arm 72 pivotally connected as at 73 to the upper end of one of the printer bars as shown in Figure 2. Each bell crank lever is further provided with a vertical arm 74 pivotally connected as at 75 with one end of a link 76. A coil spring 77 is connected at one end to the vertical arm 74 of each bell crank lever, and the opposite end of the spring is connected to a suitable portion of the frame. The opposite end of each link 76 is pivotally connected as at 78 with one of the type bars 79 of the apparatus, similar in construction to the usual type bar of a typewriter and provided with type 80. The free end of each type bar is normally supported upon a rail 81 as will be apparent. Adjacent the pivotal connection 78, each type bar is pivotally connected as at 82 with a supporting rail 83 forming a part of the frame of the type basket. It will be obvious that downward movement of the operating rod associated with each type bar will swing its bell crank lever 71 about the rod 72, thus moving the link 76 and raising the type bar to cause the type thereof to strike against a sheet of paper on the platen, in the usual manner.

As previously stated, I prefer to employ five of the operating rods for effecting the other mechanical functions of the apparatus. As shown in Figure 2, I have diagrammatically represented a block 84, the elevation of which is adapted to shift the type into the upper case. In some forms of typewriters vertical movement of this block will effect move-

ment of the type basket for accomplishing the same result. For the sake of illustration, I have shown this block as being provided with a horizontal portion 85 and a vertical portion 86, the upper end of which is provided with a shoulder 87. A bell crank lever 88 is provided with a horizontal arm 89 contacting with the lower face of the horizontal portion 85 of the block 84. The bell crank lever is 5 pivotally connected to any suitable portion of the frame of the apparatus as at 90, and is provided with an upwardly extending lever arm 91. A link 92 is pivotally connected at one end as at 93 with the upper end of the lever arm 91, and the opposite end of the link 10 92 is pivotally connected as at 94 with a bell crank lever 95 similar in construction to the bell crank lever 71 previously described and pivotally supported upon the rod 70. The horizontal arm of the bell crank lever 95 is 15 pivotally connected as at 96 to the upper end of an operating rod 97, this rod being one of the group of operating rods previously described. It will be obvious that downward movement of the rod 97 is adapted to rock the bell crank levers 95 and 88 to effect vertical movement of the block 84. As shown in Figure 2, a latch 98 is pivotally connected as at 20 99 to any suitable portion of the typewriter frame, and is provided near its lower end with a tooth 100 adapted to engage beneath the shoulder 87. A spring 101 is adapted to urge the tooth forwardly to engagement beneath the shoulder 87 when the block 84 is elevated in a manner to be described. The latch 98 is provided beneath the tooth 100 with a depending end and a slot and pin connection 102 connects this depending end with one end of a rod 103. The opposite end of the rod 25 103 is pivotally connected as at 104 with a bell crank lever 105 similar to the bell crank levers 71 and 95 previously described, and also pivotally supported by the rod 70. The horizontal arm of the bell crank lever 105 is 30 pivotally connected as at 106 with one operating rod 107 of the group previously described. When the block 84 is elevated by operation of the rod 97, the tooth 100 engages beneath the shoulder 87 and is retained in such position until the rod 107 is drawn 35 downwardly, this latter action rocking the bell crank lever 105 and drawing the rod 103 outwardly to release the tooth 100 from the shoulder 87, thus permitting the block 84 to return to normal position. It will be obvious that the latch 98 is free to swing forwardly when the block 84 is elevated without effecting movement of the rod 103, due to the slot and pin connection 102.

40 Another operating rod 108 of the group described is adapted to effect the line feed of the apparatus by operating the pawl 20. A rod 108' is arranged above the operating rod 108, and the adjacent ends of these rods 45 are pivotally connected to each other and to a link 109', the opposite end of this link being pivotally connected with the rod 70. The rod 108' has a portion 109 offset rearwardly to permit free movement of other parts of the apparatus to be described. Above the offset portion 109, the rod 108' referred to is provided with a horizontal portion 110 and a vertical portion 111. The vertical portion 111 extends upwardly to a point substantially in horizontal alignment with the rod 70 50 75 80 85 90 95 100 105 110 115 120 125 130

25, whereupon the rod extends forwardly as at 112 and is provided with an eye 113 slidably receiving the rod 25. It will be apparent that the carriage is free to move longitudinally with the rod 25 sliding within the eye 113 and that downward movement of the rod 108 is adapted to rock the bell crank lever 22, thus causing the pawl 120 to engage one of the ratchet teeth 19 to advance the platen to the next line to be printed.

30 One operating rod 114 also forming one of the group described, is operable for effecting the return of the carriage to the beginning of a line after the preceding line has been completed. A rod 114' is arranged above the rod 114 as shown in Figure 2, and the adjacent ends of these rods are pivotally connected to each other and to one end of a link 115', the opposite end of this link being pivotally connected to the rod 70. The upper end of the vertical portion 117 is pivotally connected with a lever 118, as at 119, the lever 118 being pivotally supported intermediate its ends as at 120 and secured at its opposite end to the slide 62. The slide is slidable beneath the shoulder 38 of the rack bar 36 to permit free longitudinal movement of the carriage. It will be obvious that downward movement of the rod 114 is adapted to lower the rear end of the lever 118 and elevate the slide 62, which action elevates the rack bar 36 and releases the teeth 37 thereof from the teeth of the pinion 43. Upon completion of this movement, the tension of the spring within the drum 28 rotates the drum thus winding the cable 29 and returning the carriage to the beginning of a line.

35 Means are provided for controlling the ratchet wheel 44 to move the carriage longitudinally between letters and between words. As shown in Figures 2 and 4, the numeral 121 designates a longitudinal bar pivotally connected as at 122 to any suitable portion of the frame. This bar extends along the rear portion of the apparatus adjacent the vertical arms 74 of each of the bell crank levers 71. It will be obvious that actuation of these bell crank levers is adapted to swing the bar 121 rearwardly about its pivots 122. As shown in Figures 1 and 2, the bar 121 terminates inwardly of the outer operating rods 97 and 107 so that operation of these rods and their associated bell crank levers will not swing the bar 121. It also will be obvious that since the links 109' and 115' associated

with the rods 108 and 114 have no vertical portions, operation of the latter will not swing the bar 121. The bar 121 is provided with a contact 123 insulated therefrom as at 124, and when the bar 122 swings rearwardly from normal position the contact 123 is adapted to establish electrical connection with a contact 125 connected to a lead wire 126, connection between these contacts being broken when the bar 121 swings back to normal position. It will be apparent that the contacts 123 and 125 may be placed in any suitable position with respect to the bar 121, the contact 125 being resiliently mounted upon the frame of the apparatus. The contact 123 is connected by a wire 127 with the solenoid 61, as shown in Figure 1, the opposite end of the solenoid coil being grounded as at 128 through a wire 129. A suitable source of current to be described is adapted for connection between the wire 126 and ground 128 for supplying energy to the solenoid 61.

From the foregoing it will be apparent that actuation of any of the printer bars is adapted to swing the bar 121 rearwardly to energize the solenoid 61. The armature 60 then draws the lever 54 downwardly and the tooth 52 escapes over the teeth of the ratchet wheel. As soon as the printer bars are released in a manner to be described, the bar 121 returns to normal position thus breaking electrical connection between contacts 123 and 125 and deenergizing the solenoid 61, this action causing the spring 58 to draw the lever 54 upwardly whereby the tooth 52 engages the teeth of the ratchet wheel 44 to rotate it. Rotation of the ratchet wheel obviously is adapted to space the carriage longitudinally for the next impression or word space. I also provide means for actuating the bar 121 to provide proper spacing between words. Another of the operating rods of the group 66 is adapted to accomplish the word spacing movement of the carriage. As shown in Figure 2, the rod 130 is pivotally connected at its upper end as at 131 with a bell crank lever 132 also pivotally supported upon the rod 70. The bell crank lever 132 is provided forwardly of the bar 121 with an arm or upper lever portion 133 which is adapted to swing the bar 121 rearwardly when the operating rod 130 is actuated. Thus it will be apparent that actuation of the latter operating rod is adapted to provide proper spacing between words without effecting any printing action.

As shown in Figures 1, 2, 4 and 5, a longitudinally extending striker bail or actuating rod 134 is arranged within the frame 10 near the lower rear portion thereof. The rod 134 is supported adjacent each end in one end of a supporting link 135, each of the links being pivotally supported at 136 upon any suitable portion of the frame of the apparatus. Springs 137 are adapted to normally hold

the rod 134 in its upper position. Solenoids 138 of the single spool type are arranged adjacent each end of the rod 134 and are provided with armatures 139 pivotally connected to links 140, the upper ends of the links being provided with eyes 141 surrounding the rod 134. Suitable means are provided for energizing the solenoids 138 at the proper time for effecting the downward movement of one of the operating rods 66. As shown in Figure 4, the rod 134 is arranged rearwardly of the operating rods 66 and is adapted to contact with one of the hooked portions 68 to move one of the operating rods downwardly when the solenoids 138 are energized. Means to be described are provided whereby all of the operating rods 66 except one will be moved forwardly out of the path of travel of the rod 134, as shown in dotted lines in Figure 4 of the drawings. The single operating rod 66 which is allowed to remain in the solid line position shown in Figure 4 by the selecting mechanism is arranged with the hook 68 thereof in contact with the rod 134, and it will be obvious that energization of the solenoids 138 will draw the rod 134 downwardly to effect downward movement of the operating rod 66 just referred to. When the circuit through the solenoids 138 is broken the springs 137 are adapted to return the rod 134 to normal position.

Means are provided for selecting the operating rod to be drawn downwardly by the actuating rod 134. As shown, the numerals 141, 142, 143, 144, and 145, designate a plurality of selector rods which are arranged parallel to each other and adjacent the operating rods 66. In practice I prefer to employ five of the selector rods as illustrated for a reason which will become apparent. The upper selector rod 141 is provided with a pair of cams 146 and 147 which extend outwardly from the rod 141 at right angles to each other. In Figure 2 of the drawings I have shown the selector rod 141 in normal position whereby it will be apparent that the cam 146 engages all of the operating rods 66 toward one side of the apparatus, thus forcing the lower ends of said rods forwardly against the tension of their springs 69. The operating rods thus moved forwardly have their hooked portions 68 moved out of the path of travel of the rod 134 as indicated in dotted lines in Figure 4. Since the cam 147 projects downwardly beneath the rod 141, this cam will have no effect upon the operating rods 66 toward the right side of the machine, as viewed in Figure 1 and hence the hooked portions of these rods are free to be arranged beneath the rod 134, so far as the cam 147 is concerned. As will appear however, the remaining selector rods are adapted to influence those of the operating rods 66 which are not arranged to be engaged by the cam 147. The selector rod 141 is rotatable 130

through a one-quarter circle to move the cam 146 to an upwardly extending vertical position and to move the cam 147 to the same relative position normally occupied by the cam 146, in which case the relative positions of the operating rods 66 at the right and left sides of the machine will be reversed, those previously held out of engagement by the cam 146 being released, so far as the cam 146 is concerned, and those normally free of influence by the cam 147 being moved forwardly to move the hook portions thereof out of the path of travel of the rod 134. The next lower selector rod 142 is provided with a pair of cams 148 and 149, each of which extends substantially through one-half the length of each of the cams 146 and 147. The cams 148 and 149 normally project forwardly and horizontally, and the selector rod 142 is provided with a second pair of cams 150 and 151, which normally depend vertically from the rod 142. Each of the cams of the selector rod 142 is associated with a pair of cams 152 and 153 carried by the selector rod 143, the cams 152 normally projecting forwardly and horizontally while the cams 153 normally depend vertically from the selector rod 143. Similarly each cam of the rod 143 is associated with a pair of cams 154 and 155 of the next lower selector rod 144, the cams 154 normally corresponding in position to the cams 146, 149 and 152 while the cams 155 normally correspond in position to the cams 147, 151 and 153. From an examination of Figure 1 it will be apparent that each of the cams 152 and 153 is associated with and adapted to control four of the operating rods 66 with the exception of the cam 153 at the extreme right end of the selector rod 143. This is due to the fact of course that there are thirty-one of the selector rods. The cams 154 and 155 are each adapted to control two of the operating rods 66 with the exception of the cam at the extreme right end of the selector rod 144, this cam only influencing the last operating rod 66 while the next adjacent cam influences or controls two of the operating rods 66. The lowest selector rod 145 is provided with a plurality of cams 156 and 157 each of which controls one of the operating rods 66. Each of the selector rods 141 to 145 is rotatable through a one-quarter circle to bring either set of cams carried by each selector rod into engagement with certain of the operating rods 66. The selector rods are normally arranged in the position shown in Figure 1 and are retained in such position by suitable springs 158. For the sake of simplicity, I prefer to employ torsion springs 158, one end of each spring being secured to its associated selector rod while the opposite end of each spring is secured to the adjacent side frame 11. Each selector rod is adapted to be rotated through a one-quarter circle by electrical means to be described, such move-

ment being accomplished against the tension of the springs 158 while the latter return the selector rods to their normal positions upon deenergization of the electrical means referred to. From an examination of Figure 1 it will be apparent that each of the operating rods 66 is contacted by at least one normally horizontal cam of the selector rods so that none of the operating rods is in a position to have its hooked portion 68 engaged by the rod 134. The operating rod 130, which is the word spacing rod, is the one indicated at the extreme right end of Figure 1. It will be noted that the cams at the extreme right ends of the selector rods 141 to 144 inclusive are normally vertically arranged and hence will not influence the rod 130. The cam at the extreme right end of the selector rod 145, however, normally projects horizontally to hold the word spacing rod 130 in an operative position with respect to the rod 134. It will be apparent therefore, that rotation of the lowest selector rod 145 through a one-quarter circle will release the rod 130, permitting its spring 69 to draw the lower end thereof rearwardly to place it in an operative position whereby its hooked portion 68 will be engaged by the rod 134 if the latter is moved downwardly. Similarly one or more of the selector rods may be rotated through a one-quarter circle to release any one of the rods 66 to permit the lower end thereof to swing rearwardly, only one of the operating rods being released at a time and the one released depending upon the particular selector rod or combination of selector rods rotated.

Electrically controlled means are provided for rotating the selector rods in the manner described. As shown, a plurality of single spool solenoids 159, 160, 161, 162 and 163 are supported in any suitable manner adjacent the frame of the printing apparatus. Each of these solenoids is provided with an armature 164 pivotally connected as at 165 with a link 166. The outer ends of the links are pivotally connected to the lower ends of cranks 167 secured to or formed integral with the selector rods. Energization of the solenoids in a manner to be described is adapted to rotate the selector rods.

A battery or other source of current 168 is provided for operating the electrical elements of the apparatus previously referred to. One side of the battery is grounded as at 169, while the opposite side of the battery is connected by a wire 170 with a switch arm 171 adapted to normally engage a contact 172. A spring 173 normally closes the circuit between the switch arm 171 and contact 172. The switch arm 171 is arranged as shown in Figure 2, to be actuated by downward movement of the rod 134 to open the circuit between the switch arm 171 and contact 172. The contact 172 is connected to a

common wire 174 which in turn is connected to each of the solenoids 159 to 163 inclusive through branch wires 175. A lead wire 176 is connected to the opposite end of the coil of each of the solenoids referred to. A branch wire 177 is also connected to the wire 174, the wire 177 being provided with branches 178 connected to each of the solenoids 138. The opposite ends of the coils of the solenoids 138 are connected to a lead wire 179. A branch wire 180 is connected at one end to the wire 170 leading from the battery 168, and the opposite end of the wire 180 is connected to the wire 126 to supply current to the contact 125.

Referring to Figure 1, the numerals 181 to 185 inclusive designate a plurality of electro-magnetic relays corresponding in number and arrangement to the solenoids 159 to 163 inclusive. Each of the relays is provided with an armature 186 connected to one of the wires 176. The coil of each relay is connected to a common return wire 187 which is grounded as at 188, a lamp or other resistance 189 being interposed in the wire 187 for a purpose to be described. The opposite ends of the coils of the relays 181 are connected to wires 190, and the opposite ends of these wires are connected to arcuately arranged contacts 191 carried by a distributor 192 of the Baudot type. The wires 190 are also provided with contacts 193 adapted to establish electrical connection with the armatures 186 when the relays are energized.

As previously stated, the distributor 192 is of the Baudot five point type, and means are provided for sending electrical impulses through either of the contacts 191 according to the particular selection to be made. The distributor is provided with an arcuate contact 194, and a rotatable brush member 195 is carried by the distributor. The brush 195 is mechanically rotated and is synchronized with the rotatable brush of a distributor at the sending station. As the brush 195 passes over the contact 194, it will be apparent that it is adapted to convey electrical impulses to either of the contacts 191 as it passes thereover if the contact 194 is energized at the proper time. The contact 194 is connected by a wire 196 to the tongue of a differentially wound polarized relay indicated as a whole by the numeral 197. This relay includes an armature 198 electrically connected with the wire 196 and adapted to be attracted by either of two relay magnets 199 and 200. The latter relay magnets are connected by a common wire 201, and the magnets 199 and 200 are connected with the sending station through a wire 202. The armature 198 is adapted to establish electrical connection with either of two contacts 203 or 204 according to which of the magnets of the polarized relay attracts the armature. The contact 204 is connected by a wire 205 with one terminal

of a battery or other source of current 206, the other terminal of this source of current being grounded as at 207 through a wire 208.

The wire 179 is connected with an armature 209 adapted to be operated by a relay 210. The coil of this relay is connected at one end to a wire 211 and the opposite end of this wire is connected to a stationary local contact 212 carried by the distributor 192. A coacting local contact 213 is arranged between the contact 212 and the axis of rotation of the brush 195. The brush is extended to the opposite side of its pivot to form a local brush 213' and the latter in its rotation is adapted to electrically connect the contacts 212 and 213. A wire 214 connects the contact 213 with a ground 215. The opposite end of the coil of the relay 210 is connected by a wire 216 with the common relay return wire 187.

The operation of the apparatus is as follows:

When the apparatus is being operated from a sending station connected with the line wire 202, the relay magnet 200 will be operated for each marking impulse received, thus drawing the armature 198 to the right to establish electrical connection with the contact 204. As previously stated, the rotation of the brush arm 195 is synchronized with the brush arm of the sending station, and the current impulses are received at the same instant that the arm 195 passes over one of the contacts 191. It will be obvious that for some selections an impulse will be received as the arm 195 passes over only one of the contacts 191, while for other selections any combination of current impulses may be received by the distributor 192. It will be obvious that the distributor is shown diagrammatically, and it will be apparent that any number of groups of the contacts 191 may be employed whereby the arm 195 will pass over a number of the groups during each revolution instead of a single group as illustrated.

As an impulse is received through the line wire 202, current will be transmitted to one of the relays 181 to 185 inclusive whereby current will flow from the source 206, through contact 204 and armature 198, to wire 196 and contact 194. Current then will be transmitted through the arm 195 to one of the contacts 191 depending upon the particular instant at which the impulse is given. As previously stated, however, impulses may be given as the brush 195 passes one or more of the contacts 191, whereby current will be supplied to one or more of the relays 181 to 185 inclusive, through wires 190. From the relay or relays energized, current flows to the common return wire 187, through the lamp 189 or other resistance, to ground 188, and thence back to the source 206 through ground 207 and wire 208. Actuation of one of the relays 181 to 185 inclusive in the manner de-

scribed, attracts its corresponding armature 186, which armature is connected with one of the solenoids 159 to 163 inclusive. Assuming that only the relay 185 is energized, it will be apparent that its corresponding armature 186 will be attracted, thus establishing electrical connection between this armature and the corresponding contact 193. Under such conditions, current will flow from the source 168 to switch arm 171 and contact 172, thence through wire 174 and the lowermost wire 175 to the solenoid 163, and from this solenoid current flows through one of the wires 176 to the operated armature 186. From the latter armature, current flows through the solenoid 185 to the wire 187, through the lamp 189 to ground 188, from whence it returns to the source 168 through the ground 169. Thus it will be obvious that the solenoid 163 and relay 185 will be energized, energization of the solenoid 185 being maintained after the brush 195 passes beyond the contact corresponding with this relay. It will be obvious that current may be supplied to any one or more of the solenoids 159 to 163 inclusive in the same manner, and in either case the selected relays 181 to 185 will be maintained in an energized condition after the brush 195 passes beyond the contacts 191. As previously stated, all of the operating rods 66 are held out of operative position, that is, out of the path of travel of the bar 134, when the selector rods are in normal position as shown in Figure 1. From an examination of this figure, it will be apparent that the operating rod 130 at the extreme right end of the apparatus will be held out of operative position only by one of the cams 156 of the lowermost selector rod, the operating rod 130 being cleared so far as the remaining selector rods are concerned. Energization of the solenoid 163 in the manner described attracts the armature of the solenoid, thus drawing the corresponding crank 167 inwardly to rotate the lower selector rod through a quarter circle. Under such conditions, the cam 156 which normally holds the operating rod 130 out of normal position is moved to inoperative position and the spring 69 corresponding to the operating member referred to, draws this member rearwardly to arrange its hooked portion 68 directly beneath the rod 134 to be actuated thereby when it is moved downwardly in a manner to be described.

As previously stated, either of the solenoids 159 to 163 inclusive, or any combination of such solenoids previously selected will be maintained energized after the brush has passed off the contacts 191, thereby holding the selector rods in any desired position for a given selection of an operating rod 66. Means are provided for automatically depressing the rod 134 to operate the rod thus selected, and to permit the selected elements

to return to normal position after the actuating rod has completed its movement. After the brush arm 195 passes beyond the contacts 191, rotating in a counter-clockwise direction, the local brush 213' is adapted to bridge across the contacts 212 and 213. If either of the relays 181 to 185 inclusive has been previously energized, some of the current then will flow through the relay 210, and wire 211, thence across the contacts 212 and 213 through arm 195, through wire 214 and ground 215, and back to the source 168 through the ground 169. Passage of current through the relay 210 is made possible by interposing the lamp or other resistance 189 in the wire 187. When the relay 210 is energized it attracts its armature 209, thus closing a circuit from the wire 174, previously energized in the manner described, through wires 177 and 178 to the solenoids 138, thence through wire 179 to the armature 209. From the armature 209, some of the current flows through the solenoid 210, wire 187 and lamp 189, to ground 188 and thence back to the source 168, through ground 169. Thus the relay 210 also will be maintained energized after the brush arm 195 has passed beyond the contacts 212 and 213. The closing of the circuit last referred to obviously energizes the solenoids 138 thus attracting their armatures 139 and drawing the rod 134 downwardly against the tension of the springs 137. With the selection previously referred to, wherein only the lowermost selector rod has been rotated through a one-quarter circle, it will be apparent that downward movement of the rod 134 will depress the operating rod 130. This action swings the bell crank lever 132 and the upper arm 133 of this lever contacts with the bar 121 to swing the latter rearwardly and establish electrical connection between the contacts 123 and 125. As the actuating rod 134 approaches the lower limit of its movement, the switch 171 will be opened, since the switch is arranged in the path of travel of either the rod 134 or one of its supporting links 135. This action breaks the circuit between the switch arm 171 and contact 172, thus deenergizing all of the selector rod solenoids, and all of the relays. The solenoid 61 is in a normally open circuit and therefore the spring 58 normally holds the arm 54 in its upper position. Energy for the circuit of solenoid 61 is supplied through wires 170, 180 and 126, contacts 123 and 125, and wire 127. From the solenoid current returns to the source 168 through wire 129 and grounds 128 and 169. It will be obvious that when the circuit for the solenoid 61 is completed, it is broken by movement of the bar 121 back to normal position and spring 58 will draw the pawl 51 upwardly, the tooth 52 of the pawl engaging the teeth of the ratchet wheel to rotate it and move the carriage one space. It will be apparent that

the spacing action referred to will not be carried out if either of the operating rods 97, 107, 108 or 114 is operated, since none of these rods is provided with means associated with the bar 121 to cause actuation of the latter. The spacing rod 130, and all of the operating rods associated with characters to be printed, however, are provided with bell crank levers having portions adapted to actuate the bar 121 whereby the carriage is moved longitudinally one space after the completion of the operation of any of the elements last referred to. The instant the circuits through the selector solenoids, and the solenoids 138 are broken, the springs 137 tend to return the rod 134 to its upper or normal position, and this return movement tends to take place ahead of the upward movement of the operating rod which has been operated, due to the greater inertia of the parts brought into operation by the operating rod. This lagging movement of the operating rod while extremely slight, is sufficient at least to loosen the contact between the rod 134 and the hooked portion of the operating rod. Deenergization of the selector solenoids permits the selector rods to return to normal position and at least one of the selector cams will contact with the previously selected operating rod to return it to normal position, and this action is quickly completed due to the small amount of force necessary to move the previously selected operating rod, the friction between the hooked portion of the rod and the rod 134 having been reduced in the manner previously described.

An examination of Figure 1 will make it clear that selection of any one or more selector rods is adapted to release one of the operating rods for engagement with the actuating rod 134. For instance, the shift release rod 107 is normally held in inoperative position by all of the selector rods, and accordingly it is necessary to actuate all of the selector solenoids in order to release the shift release for operation. Similarly the case shift rod 97 is held in inoperative position by cams of the four uppermost selector rods, but not by the lowermost selector rod, and accordingly it is necessary to energize solenoids 159 to 162 inclusive in order to effect movement of the case shifting mechanism. Similarly any of the operating rods may be selected by actuation of any one or more of the selector solenoids.

The line feeding pawl and ratchet mechanism is controlled by movement of the operating rod 108. As shown in Figure 1, this rod is normally held in inoperative position by the normally horizontal cams of selector rods 141, 142, 143 and 145, and accordingly it is necessary to energize solenoids 159, 160, 161 and 163 to effect movement of the line feed mechanism. When this action is ac-

complished, the operating rod 108 is actuated by the rod 134, this action drawing the rods 108 and 108' downwardly, thus operating the pawl 20 as will be obvious. This action of course is carried out at the end of each line, and movement of the carriage to the beginning of the next line is effected by movement of the operating rod 114. This rod is normally maintained in inoperative position by the normally horizontal cams of selector rods 141, 142 and 143, and accordingly may be brought into operative position by energization of solenoids 159, 160 and 161. After selection of this rod downward movement of the actuating rod 134 causes the downward movement of rods 114 and 114', and this movement again rocks the rod 118 about its pivot 120, thus lifting the slide 62. Elevation of the slide 62 lifts the rack bar 36 and causes the horizontal portion of the latch 64 to swing inwardly and thus hold the rack bar in its uppermost position with the teeth 37 thereof out of engagement with the teeth of the pinion 43. The spring 33 then rotates the drum 28, thus winding the cable 29 about the drum and returning the carriage to the beginning of the next line.

As the carriage approaches the limit of its movement at the start of a line, the stop 66 contacts with the depending portion 65 of the latch 63, causing the latter to swing outwardly longitudinally of the carriage to release the horizontal portion 64 of the latch from the rack bar thus permitting the latter to return to normal position with the teeth of the rack bar in engagement with the pinion 43.

The operation of the case shift and shift release mechanisms will be obvious from an examination of Figure 1. Actuation of the rod 97 swings the bell crank lever 88 about its pivot thus elevating the block 84, the latter being held in its upper position by the latch 98. Actuation of the rod 107 releases the latch 98 permitting the shift release action to take place.

It will be obvious that the cams of the selector rods are placed varying distances from the upper pivot points of the operating rod, and accordingly the cams of the lower selector rods are preferably of increasing width to compensate for the increased distance from the centers of the lower selector rods to the operating rods when the latter are in inoperative position as shown in dotted lines in Figure 4.

From the foregoing, it will be apparent that I provide a relatively simple apparatus wherein selection of a character to be printed or a mechanical function to be performed may be accomplished in a very short interval of time, actuation being accomplished promptly upon completion of the selection. The actuating mechanism obviously is adapted to automatically break the circuits through the controlling solenoids and relays, thus per-

mitting the latter elements to promptly return to normal position. The present apparatus eliminates the use of constantly running motors, and materially reduces the interval of time necessary for the completion of any function, due to the rapid action of the solenoids and relays. With present devices of this character a considerable interval of time is necessary for the performance of the various functions of the apparatus due to the use of friction clutches, and the necessity for overcoming the inertia of relatively heavy parts, such as gears and the like. The present apparatus is adapted to employ very light operating parts, the inertias of which are substantially negligible whereby practically instantaneous operation is accomplished.

The electrically operated elements of the apparatus are deenergized when no messages are being received since energization of the relays is dependent upon impulses received from the sending station while energization of the selector solenoids and the solenoid 61 is dependent upon energization of the selector relays. It also will be apparent that energization of the relay 210 is dependent upon the pre-selection of at least one of the relays 181 to 185 inclusive, since current is initially supplied to the relay 210 through the common return wire 187. Therefore if the brush 195 passes over all of the contacts 191 without transmitting any impulses thereto, it will be obvious that the relay 210 will remain deenergized and no actuation of the rod 134 will take place. Thus it will be obvious that the apparatus is not only extremely simple in construction and operation but may be economically operated so far as the consumption of current is concerned.

40 The line wire 202 may be employed for sending and receiving messages simultaneously through the operation of the differentially wound polar relay 197.

It is to be understood that the form of the invention herewith shown and described is to be taken as a preferred example of the same and that various changes in the shape, size and arrangement of parts may be resorted to without departing from the spirit of the invention or the scope of the subjoined claims.

50 I claim:

1. A page printing telegraph machine comprising typewriting mechanism including a plurality of operating members, mechanical selecting means for said operating members operative in either of two positions and having a normal bias to one of such positions, electro-magnetic means adapted to directly actuate said selecting means to move them to the other of said positions, means for actuating the operating member selected by said selecting means, a source of current adapted to be connected to said electro-magnetic means, and a switch controlled by movement 65 of said actuating means for disconnecting

said source of current from said electro-magnetic means upon the operation of the selected operating member.

2. A page printing telegraph machine comprising typewriting mechanism including a plurality of operating rods, a plurality of mechanical selecting means for said operating rods each operative in either of two positions and having a normal bias to one of such positions, an electro-magnet adapted to actuate each of said selecting means to move it to the other of said positions, a source of current for said electro-magnets, means for actuating the operating rod selected by said selecting means, and means controlled by said actuating means for disconnecting said source of current from said electro-magnet upon the operation of the selected operating rod.

3. A page printing telegraph machine comprising typewriting mechanism including a plurality of operating rods, a plurality of oscillatory selecting devices each movable to either of two positions and having a normal bias to one of said positions, an electro-magnet directly connected to each of said selecting devices to move it to the other of its positions, a source of current for said electro-magnets, a switch adapted to control a supply of current from said source to said electro-magnets, and an actuating device for the operating rod selected by said selecting devices, said switch being operable by movement of said actuating device to disconnect said electro-magnets from said source of current upon the operation of the selected operating rod.

4. A page printing telegraph machine comprising typewriting mechanism including a plurality of operating rods, a plurality of mechanical selecting devices for said rods, each of said selecting devices including a plurality of correlated cams adapted to engage said operating rods, each of said selecting devices being movable to either of two positions and having a normal bias to one of such positions, an electro-magnet directly connected to each of said selecting devices to move it from normal position to the other of its positions, a source of current for said electro-magnets, and actuating means for the operating rod selected by said selecting devices, said actuating means being adapted to open said switch upon the movement of the selected operating rod.

5. A page printing telegraph machine comprising typewriting mechanism including a plurality of parallel operating rods, a plurality of parallel selector rods, said selector rods being arranged at right angles to said operating rods and in a plane parallel to the plane thereof, each of said selector rods being provided with a plurality of correlated cams adapted to contact with said operating rods to move them to operative and

inoperative positions, each of said selector rods being movable to either of two positions and having a normal bias to one of such positions, a plurality of electro-magnets each having an armature connected to one of said selector rods, a source of current, a switch adapted to control the supply of current to said electro-magnets, a plurality of electrical selecting means adapted to control the passage of current to said electro-magnets independently of said switch, and an actuating rod for said operating rods, said actuating rod being adapted to open said switch upon the movement of one of said operating members.

6. A device constructed in accordance with claim 5 provided with electro-magnetic means for operating said actuating rod, and means for connecting said electro-magnetic means to said source of current independently of the energization of said electro-magnets.

7. A device constructed in accordance with claim 5 provided with means for supporting said actuating rod to permit its movement from inoperative to operative positions, said actuating rod having a normal bias to inoperative position, and electro-magnetic means for operating said actuating rod.

8. A page printing telegraph machine comprising typewriting mechanism including a plurality of operating rods, mechanical selecting devices for said rods operative in either of a plurality of positions and having a normal bias to one of such positions, an electro-magnet adapted to actuate each of said selecting devices, a relay associated with each of said electro-magnets, a source of current, a distributor adapted to supply electrical impulses to either of said relays, a second source of current for said electro-magnets, energization of either of said relays being adapted to connect it in circuit with its associated electro-magnet, an actuating rod adapted to effect movement of the operating rod selected by said selecting devices, and having a normal bias to inoperative position, a solenoid controlling movement of said actuating rod, said solenoid being connected to said second named source of current, and means controlled by the movement of said actuating rod for disconnecting said electro-magnets, said relays and said solenoids from said source of current upon completion of the movement of the selected operating rod.

9. A page printing telegraph machine comprising typewriting mechanism including a plurality of operating rods arranged parallel to each other, a plurality of selector rods arranged parallel to each other at right angles to said operating rods, said operating rods and said selector rods being arranged in adjacent parallel planes, a plurality of co-related cams carried by each of said selector rods and adapted to engage said operating rods to

move them to operative and inoperative positions, each of said selector rods being movable to either of two positions and having a normal bias to one of such positions, an electro-magnet adapted to move each of said selector rods from its normal position to the other of its positions, an actuating rod movable from inoperative to operative position to effect movement of an operating rod selected by said selector rods and having a normal bias to inoperative position, a solenoid controlling movement of said actuating rod, a relay associated with each of said electro-magnets and provided with an armature connected in circuit with one end of the coil of each of said electro-magnets, a source of current having one side connected to the opposite ends of said coils, a distributor having a plurality of contacts, a wire connecting each contact to one end of the coil of each relay and adapted to be electrically connected to the armatures of said relays upon energization thereof, a second source of current adapted to transmit electrical impulses to each of said contacts, the opposite ends of the coils of said relays being connected to the opposite side of said first named source of current, and means controlled by said distributor for energizing said solenoid.

10. A device constructed in accordance with claim 9 provided with means controlled by the movement of said actuating rod for disconnecting said first named source of current from the coils of said electro-magnets.

11. A page printing telegraph machine comprising typewriting mechanism including a plurality of operating members, mechanical selecting means for said operating members operative in a plurality of positions and having a normal bias to one of such positions, said operating members being constantly in engagement with said selecting means, and electro-magnetic means adapted to actuate said selecting means.

12. A page printing telegraph machine comprising typewriting mechanism including a plurality of operating members, mechanical selecting means for said operating members operative in a plurality of positions and having a normal bias to one of such positions, electro-magnetic means adapted to actuate said selecting means, and actuating means for the operating member selected by said selecting means, said operating members being constantly in engagement with said selecting means and having a normal bias to operative position to be engaged by said actuating means.

13. A page printing telegraph machine comprising typewriting mechanism including a plurality of operating members arranged substantially in a common plane, a plurality of oscillatory selecting members provided with a plurality of co-related cams and arranged adjacent said operating mem-

bers, said operating members constantly engaging said selecting members, and means for actuating the selected operating member.

14. A page printing telegraph machine comprising typewriting mechanism including a plurality of operating members, a plurality of oscillatory selecting members provided with a plurality of corelated cams, said selecting members being operative in either of two positions and having a normal bias to one of such positions, means for maintaining said operating members in constant engagement with said selecting members, and means for actuating the selected operating member.

15. A page printing telegraph machine comprising typewriting mechanism including a plurality of operating members arranged substantially in a common plane, a plurality of oscillatory selecting members arranged adjacent said operating members substantially at right angles thereto and in a plane substantially parallel to the plane thereof, said selecting members being operative in either of two positions and having a normal bias to one of such positions, means for maintaining said operating members in constant engagement with said selecting members, each of said operating members being provided with a shoulder, and actuating means adapted to engage the shoulder of and to move the selected operating member.

16. A page printing telegraph machine comprising typewriting mechanism including a plurality of operating members, a plurality of selector rods arranged parallel to each other in a plane substantially parallel to said operating members, said selector rods being provided with a plurality of corelated cams and being operative in either of two positions, means constantly urging said selector rods to one of said positions constituting normal position, means for moving said selector rods to the other of said positions, said operating members being arranged in constant engagement with said selector rods, and means for engaging and actuating the selected operating member.

17. A page printing telegraph machine comprising typewriting mechanism including a plurality of operating members, a plurality of selector rods arranged parallel to each other in a plane substantially parallel to said operating members, said selector rods being provided with a plurality of corelated cams and being operative in either of two positions, means constantly urging said selector rods to one of said positions constituting normal position, means for moving said selector rods to the other of said positions, said operating members being arranged in constant engagement with said selector rods, means for engaging and actuating the selected operating member, and means operative upon movement of said actuating means for releasing the selector rods which have been

moved from normal position, to permit them to return thereto.

18. A page printing telegraph machine comprising typewriting mechanism including a plurality of operating members, a plurality of selector rods arranged adjacent said operating members and including a plurality of corelated cams, said selector rods being operative in either of two positions and having a normal bias to one of such positions, means for moving said selector rods to the other of said positions, means associated with said last named means for momentarily retaining said selector rods in said last named position when moved thereto, said operating members being in constant engagement with said cams, means for actuating the selected operating member, and means operative upon movement of said actuating means for releasing the selector rod retaining means.

19. A page printing telegraph machine comprising typewriting mechanism including a plurality of operating members, a plurality of selector rods supported at their ends for axial oscillation and provided with a plurality of corelated cams, said selector rods being operative in either of two positions and having a normal bias to one of such positions, means for moving said selector rods to the other of said positions, means for maintaining said operating members in constant engagement with said selector rods, and means for actuating the selected operating member.

20. A page printing telegraph machine comprising typewriting mechanism including a plurality of operating members, a plurality of selector rods supported at their ends for axial oscillation and provided with a plurality of corelated cams, said selector rods being operative in either of two positions, spring means for constantly urging said selector rods to one of such positions, means for moving said selector rods to the other of said positions, means for maintaining said operating members in constant engagement with said selector rods, and means for actuating the selected operating member.

In testimony whereof I affix my signature.

CHARLES BYRON HARRISON.
